CATHODE RAY TUBE SYSTEM

Henry B. De Vore, Newark, N. J., assignor to
 Radio Corporation of America, a corporation of
 Delaware

Application August 23, 1940, Serial No. 353,792

6 Claims. (Cl. 250—27)

My invention relates to television transmitting tube systems of the cathode ray type and is more particularly directed to tubes and systems utilizing low velocity electron scanning beams.

In television pick-up tubes using low-velocity electron scanning, such as the type described by Rose in United States Patent 2,213,174, it is customary to employ as a source of electrons the combination of a thermionic cathode, a grid, and a small limiting aperture which is maintained at a positive potential. This limiting aperture serves to define the electron beam by selecting from the total electron emission from the cathode a small fraction which traverses this aperture and forms the scanning beam. These electrons may have a distribution of radial velocities relative to the direction of the beam, owing to curvature of the accelerating field and to the radial components of their emission velocities from the cathode surface. There is also a corresponding distribution of longitudinal velocities possessed by the electrons of the beam.

In order to focus the beam to a small spot at the surface of the target, a uniform longitudinal magnetic field is provided. This has the characteristic that the paths of the individual electrons are helices having a diameter proportional to the radial velocity. The beam as a whole expands to some maximum diameter which is determined by these spirals and again contracts to approximately its original size at a number of points of focus between the cathode and target. I have found that these spirals are executed in a time which is uniform for all electrons, and the effect of the variation in longitudinal velocity is that the electrons do not all return to their original radial distance from the beam axis at the same distance from the limiting aperture, and consequently each successive beam focus is less sharp than the preceding. Thus, the electron beam as focused at the target forms a spot which is considerably larger than the limiting aperture at which the beam originates. The size of this spot depends on the radial velocities of the electrons in the beam and in the corresponding departure from uniformity of their longitudinal velocities.

A large scanning spot is undesirable since, as the electron density decreases toward the edge of the spot, the rate of discharge of a charged element of the mosaic is comparatively slow, and a signal corresponding to the element is transmitted during a comparatively long time. This results in a reduction of resolution in the transmitted image.

It is an object of my invention to provide a tube having a target on which an electron beam is magnetically focused wherein the electron beam may be focused to a smaller effective diameter on the target, whereby the resolution capability of the tube is increased; and it is a further object to provide a tube of the type described wherein the effective diameter of the electron beam and consequently the tube resolution is substantially independent of electron beam current.

In accordance with my invention I provide an apertured electrode structure for use in magnetically focused cathode ray tubes wherein the apertures of the electrodes are so proportioned and the electrodes so spaced as to limit the diameter of the beam and select the electrons having the desired radial and longitudinal velocities in order to focus the beam to a small spot at the surface of a beam receiving target.

A better understanding of my invention will be obtained and other objects, features and advantages will appear from the following description taken in connection with the accompanying drawing in which:

Fig. 1 is a longitudinal sectional view of a television transmitting tube embodying my invention, Fig. 2 is a cross-section of the tube shown in Fig. 1 taken along the lines 2—2, and

Figs. 3 and 4 are greatly enlarged views of a portion of the structure shown in Fig. 1 showing certain electron trajectories.

In general, the tube incorporating my invention comprises an evacuated envelope having a target preferably of the photosensitive mosaic type at one end and an electrode assembly including an electron emitting cathode and an electron collecting electrode at the opposite end of the tube. The target, if of the mosaic type, is provided on its front surface with an extremely large number of mutually insulated photosensitive particles and is so positioned that it may be scanned by an electron beam from the gun and may also have focused upon it an optical image of the object of which a picture is to be transmitted.

Intermediate the collecting electrode and the target I provide two or more electrostatic deflection plates wholly immersed in a magnetic field coaxial with the center line of the gun and the target to scan the electrons from the gun over the mosaic electrode. The potentials between the cathode and target are so adjusted that the electron beam is projected at relatively low velocity and impinges upon the target at extremely low or substantially zero velocity, that is, with a

velocity approaching zero at the point of impact. In operation, the electrostatic image, consisting of charges proportional to the intensity of the incident light, is neutralized by the low velocity beam to generate electrical signals representative of the optical image.

Referring specifically to my tube structure shown in the drawing, the tube comprises an evacuated envelope 1 enclosing at one end a target or mosaic electrode 2 and at the opposite end an electrode assembly 3 adapted to project electrons from a cathode toward the mosaic electrode.

The mosaic electrode 2 which faces the electron gun 3 preferably comprises a substantially transparent sheet of insulation such as the mica sheet 4 having on its rear surface a translucent or semitransparent electrically conducting film 5, the opposite or front surface of the mica sheet facing the electron gun being provided with an exceedingly great number of mutually separated photosensitive particles 6. In making the mosaic electrode 1 I coat one side of the mica sheet 4 with a film 5 of metal of sufficient thinness as to be substantially transparent so that an optical image such as represented by the arrow 7 may be focused on the photosensitive particles 6 by a lens system 8. The mosaic of mutually separated particles may be made by depositing on the front surface of the mica sheet 4 finely divided silver oxide which is reduced to provide a surface of individually separated silver particles or globules 6 which are subsequently oxidized and sensitized with caesium or other alkali metal during the evacuation process. Such an electrode structure and method of sensitization is well known in the art.

Intermediate the electrode assembly 3 and the mosaic electrode 1 I provide two deflection plates 9 which are curved to provide a uniformly increasing and decreasing electrostatic deflection field, a pair of shield plates 10-11, one on either side of the deflection plates 9, having slots 12-13 for the passage of the electron beam from the cathode and a conductive wall coating 14. The plates 9 are connected to ground and to the shield plates 10-11 and coating 14 through a center-tapped resistance of one to ten megohms and to a source of deflection potential. To produce the desired deflection and focus of the electron beam I provide means to wholly immerse the deflection plates in a uniform magnetic field which is preferably generated by a magnetic coil 15 of slightly larger diameter than the envelope 1 extending over and beyond the space between the electron gun 3 and the mosaic electrode 2. The deflection plates 9 in combination with the field produced by the coil 15 deflect the beam in a plane midway between the plates and through the center line of the electrode assembly 3 and target. Deflection of the electron beam in a direction normal to that produced by the plates 9 is accomplished by a pair of deflection coils 16. This deflection is preferably the frame or vertical deflection, and since in standard television systems the frame deflection is of lower frequency than the horizontal line deflection, the coils 16 should preferably be operated at the lower of the two frequencies. The deflection coils 16 may, of course, be replaced by a second pair of deflection plates. In operation, the electron beam from the cathode is focused on and scanned over the mosaic electrode 2 to discharge the electrostatic charges developed by light focused thereon. The semi-transparent film 5 is maintained at substantially cathode potential by a connection

through the output impedance 17 to the battery 18 and signals are generated across the output impedance 17 and applied to the translating device 19 in a manner well known in the art.

In part, the electrode assembly 3 includes a cathode 20 such as of the conventional indirectly heated type having an electron emitting coating 21 arranged in a position normal to the tube axis and facing the target 2. Surrounding the cathode 20 I provide a control electrode or grid 22 having a relatively large aperture axially aligned with the cathode 20. Further removed from the cathode 20 than the grid 22 there is provided an electron accelerating electrode or anode 23 similarly apertured and aligned with the grid 22 and cathode 20.

In accordance with my invention and between the anode 23 and shield electrode 11 I provide two apertured electrodes having selected aperture diameters and predetermined spacing between adjacent surfaces of the electrodes. More particularly, the electrodes 24 and 25 are positioned between the anode 23 and shield electrode 11 with their apertures 26 and 27 axially aligned with the cathode and the apertures in the other electrodes to allow electrons to flow from said cathode through said apertures and toward the target 2. While I have shown a separate anode 23, it will be understood that the function of this anode may be served by the apertured electrode 24, since said electrode is maintained positive with respect to the cathode by the battery or other potential source 18. The aperture 26 in electrode 24 will be referred to hereinafter as the beam limiting aperture 26, and the aperture 27 in the electrode 25 as the electron selecting aperture 27. In operation, the diameter of the electron beam is limited by the aperture 26 and the desired electrons passing through this aperture are selected and passed by the aperture 27 and directed toward and scanned over the target 2. Electrons of the beam not reaching the target return in the direction of and are collected by the electrode 25. For this reason the electrode 25 is preferably elongated to collect the electrons returning through the slot 12 in the shield plate 10. The returning electrons are modulated in intensity in accordance with the light and shade areas of an optical image on the target 2, and consequently the impedance 17 may be located in the electrode 25 to potential source circuit but the previously described connection for this impedance is preferred.

Referring to Fig. 3, I have shown the apertured electrodes 24 and 25 separated by an axial distance designated L_r . The aperture 26 which is for the purpose of limiting the electron beam diameter may be circular, rectangular, or of other shape, but when I refer to the diameter or radius of this aperture 26, it will be understood that this is the diameter of a circular aperture or of a circle in which the rectangular or other-shaped aperture may be inscribed, this being likewise true of the electron selecting aperture 27 in the electrode 25.

I have found that electrons liberated, such as from a cathode located in an axial magnetic field which are not emitted in a direction parallel with the field, acquire a motion which is not parallel with the field. Thus, electrons emitted with an initial radial velocity describe helical paths about an axis through the point of emission and parallel with the magnetic field. The electrons of the beam which possess radial velocities return to a point of focus following each helical revolution

about the axis. This point of focus may be referred to as a focal point of the beam or as a nodal point of the envelope of the paths traversed by the electrons of the beam emitted from the point of origin. Two such nodal points are indicated in Fig. 3, one lying within the aperture 26 and the other lying along the axis such as at a point 28, at which point the target 2 on which the beam is focused may be assumed as being located. The target 2 is shown in Fig. 3 at the nodal point 28 for purposes of explanation, although in practice the target 2 will actually be located at a subsequent nodal point. The distance between these focal or nodal points is determined by the strength of the magnetic field and the velocity of the beam electrons and may be termed the length of one loop of focus. In Fig. 3 I have shown an envelope of electrons bounded by the full lines 29, these being the selected electrons capable of passing through the electron selecting aperture 27. The electrons having greater radial velocities than the electrons bounded by the lines 29 such as represented by the envelope enclosed between the lines 30 are collected by the selecting apertured electrode and prevented from flowing to the target. In the absence of the selecting apertured electrode 25, these electrons would continue to the target along paths within the envelope bounded by the lines 31. It will be noted that while the electrons of the beam bounded by the lines 29 return to a focused condition at the nodal point 28, the electrons bounded by the lines 30 would, if allowed, continue towards the target to be focused at a different nodal point 32 displaced from the target 2.

While Fig. 3 shows the effect of the electron selecting aperture on an electron beam assumed as having a nodal point on the axis within the aperture, in practice, the electrons flowing through the aperture 26 may be considered as originating at various points within the aperture 26. Fig. 4 shows a limiting condition where one of these points of origin is at the edge of the limiting aperture. The full line 33 represents the projected trajectory on a plane through the focal points of an electron having the maximum radial velocity which it is desired to retain in the electron beam. It will be observed that the electron trajectory is terminated at the target 2, displaced by a distance equivalent to the radius of the aperture 26. An electron having a greater radial velocity and correspondingly lower axial velocity than the electron whose projected trajectory is represented by the line 33 will follow such a path as 35 which is intercepted by the selecting apertured electrode 28 and prevented from continuing along its normal path 36 to a point on the target which may be displaced from the axis by a greater distance than the radius of aperture 26. Therefore, in accordance with my invention, I reject from the electron beam all electrons which have a radial velocity in excess of a small predetermined value. From a number of tubes made in accordance with my invention I have found considerable improvement in resolution and fidelity of reproduction of the optical image replica when electrons having a radial volt velocity in excess of 0.6 volt are rejected, and even greater improvement when electrons having a radial volt velocity in excess of 0.2 volt are rejected from the electron beam. In the latter case I have also found little or no decrease in resolution with increasing beam current.

The following calculations will serve to illustrate my method of determining the proper radii of the apertures and the spacing between the beam limiting and electron selecting electrodes, in accordance with my invention.

If an electron enters a space in which there exists a uniform magnetic field and no electrostatic field, its path is a helix having its axis in the direction of the magnetic field. The projection of this helix upon a plane perpendicular to the field is a circle which is tangent to the radial component of the initial electron velocity at the point at which the electron enters the field. The speed of the electron in the projected circle is constant and equal to the initial radial velocity component. The radius of this projected circle is, (see Maloff and Epstein, "Electron Optics in Television," page 151).

$$R = \frac{v_r}{H \frac{e}{m}} \quad (1)$$

where

25 v_r =initial radial velocity component
 H =magnetic field intensity

$\frac{e}{m}$ =electron charge to mass ratio

30 If the electron enters the magnetic field at the point P_0 , its distance r from the magnetic field line passing through P_0 at a time t seconds later is given by

$$35 \quad r = 2R \sin \frac{\theta}{2} \quad (2)$$

in which θ is the angular displacement of the electron around the projected circle such that

$$40 \quad \theta = \frac{v_r t}{R} \quad (3)$$

Combining (1) and (3)

$$45 \quad 0 = H \frac{e}{m} t \quad (4)$$

Hence combining (1), (2) and (4)

$$50 \quad r = 2 \frac{v_r}{H \frac{e}{m}} \sin \frac{H \frac{e}{m} t}{2}$$

If the electron has an initial velocity component v_o in the direction of the field, then as this velocity component is unaffected by the magnetic field, the distance L_r which the electron moves in the direction of the field in the same time t is

$$60 \quad L_r = v_o t \quad (5)$$

Substituting for t it is seen that an electron in moving a distance L_r along the field suffers a radial displacement r of

$$65 \quad r = 2 \frac{v_r}{H \frac{e}{m}} \sin \frac{H \frac{e}{m} L_r}{2 v_o} \quad (6)$$

The magnetic field intensity required for proper operation of the tube shown in Fig. 1 is determined by the initial longitudinal velocity component, the distance L from the limiting apertured electrode 23 to the target 2 and the number of loops of focus occurring along the path of the electron beam between the cathode

and target. From the above cited reference the length of one loop of focus is known to be

$$1 = \frac{2\pi v_0}{H \frac{e}{m}} \quad (7)$$

For normal operation with n loops of focus

$$L = n1 = \frac{2\pi nv_0}{H \frac{e}{m}} \quad (8)$$

or

$$H \frac{e}{m} = \frac{2\pi nv_0}{L} \quad (9)$$

Substituting in (6)

$$r = \frac{L}{n\pi} \frac{v_r}{v_0} \sin \frac{\pi n L_r}{L} \quad (10)$$

It is well known that the velocity of an electron is proportional to the one-half power of the accelerating potential. Therefore, with a potential of V_o volts on the limiting and selecting apertured electrodes 23-24 with respect to cathode potential and a radial volt velocity of V_r volts

$$r = \frac{L}{n\pi} \sqrt{\frac{V_r}{V_o}} \sin \frac{\pi n L_r}{L} \quad (11)$$

This expression for the displacement r may be used in determining the relationship between the aperture diameters and the spacing between the limiting and selecting electrodes. However, ease of manufacture with respect to obtaining the desired aperture sizes, alignment and spacing, favors the use of small spacings such as 0.5 inch or less. Therefore, the selecting apertured electrode is preferably located along the first loop of focus from the cathode. Likewise the number of loops of focus is usually small, less than 10, and as a consequence, L_r is small compared with

$$\frac{L}{n\pi}$$

The above expression for r under these conditions may be simplified to

$$r = L_r \sqrt{\frac{V_r}{V_o}} \quad (12)$$

In the above analysis the longitudinal velocity was represented by v_0 (corresponding to V_o volts) which is the longitudinal velocity of the electron beam between the apertured electrodes 24 and 25, assuming the electrodes 24 and 25 at a common potential such as obtained when the switch S in Figure 1 is thrown to the right-hand position. If, however, the two apertured electrodes are maintained at different potentials with respect to the cathode, such as by throwing the switch S to the left-hand position, the above equations must be modified because if the electrons acquire or lose velocity in the space between these electrodes, the time these electrons are between the electrodes will vary. Therefore, the expression sin

$$\frac{H \frac{e}{m} t}{2}$$

must be modified if the two electrodes are maintained at different potentials. If the limiting apertured electrode is at a potential of V_o and the selecting apertured electrode is at a potential

of V_o , which is the final accelerating potential, Equation 11 becomes

$$r = \frac{L}{n\pi} \sqrt{\frac{V_r}{V_o}} \sin \frac{n\pi L_r}{L} \frac{2\sqrt{V_o}}{\sqrt{V_o} + \sqrt{V_o'}} \quad (13)$$

Again, if for the reasons outlined following Equation 11 above, the separation between the limiting and selecting apertured electrodes is made small, the expression 13 may be simplified to

$$r = L_r \sqrt{\frac{V_r}{V_o}} \frac{2}{1 + \sqrt{\frac{V_o'}{V_o}}} \quad (14)$$

If, however, the potential V_o is not the final accelerating potential, but a potential different from V_o or V_o' with respect to the cathode is applied to electrodes effective on the electron beam between the selecting apertured electrode 24 and the target and close to the electrode 24 such as to the shield plate 11, the above Equation 14 is not modified.

An electron in order to pass through both the limiting and selecting apertures may not have a displacement greater than the sum of the radii of these apertures. If the selecting and limiting apertures are separated by a distance L_r to remove electrons with a displacement greater than r , then the sum of the radii of the two apertures is properly determined equal to r . For this condition, electrons having a radial volt velocity equal to or less than V_r will be selected and passed by the selecting aperture, and all electrons having a velocity in excess of V_r will be rejected from the beam.

Assume that it is desirable to reject electrons having radial velocities greater than 0.6 volt from a beam having an average mean longitudinal velocity of 200 volts. Then, from Equation 12

$$\frac{r}{L_r} = \sqrt{\frac{0.6}{200}} = \frac{1}{18.2}$$

As shown in connection with Fig. 4, the maximum displacement of an electron is represented by the case of an electron just grazing and leaving the edge of the limiting aperture and grazing the opposite edge of the selecting aperture. Then, if in the case considered, the limiting aperture has a diameter of 0.002 inch (radius=0.001 inch), and a diameter of 0.006 inch (radius=0.003 inch) is chosen for the selecting aperture, the maximum displacement of an electron permitted by this system is

$$r = 0.001'' + 0.003'' = 0.004''$$

and the proper separation of the two apertures is

$$L_r = 18.2 \times 0.004'' = 0.073''$$

Thus, with a spacing of 0.073 inch between the limiting aperture and selecting aperture, electrons having a radial velocity in excess of 0.6 volt will be withdrawn from the beam, thereby providing an electron beam which, when focused on the target by the magnetic field, has a smaller effective diameter than a beam merely limited by a limiting aperture, and consequently the resolution of which the tube is capable will be increased. Similarly, if it be desired to reject electrons having a radial volt velocity greater than 0.2 volt from an electron beam having a mean longitudinal velocity of 200 volts, the spacing between the electrodes 23 and 24 will be 0.126 inch.

In the above examples it was assumed that

the electron beam had substantially constant longitudinal velocity between the electrodes 23 and 24. If, however, the potentials with respect to the cathode applied to these electrodes are unequal, Equations 13 and 14 apply. I have found no particular advantage in maintaining the electrodes at different potentials except possibly a slight suppression of secondary electrons originating at the limiting aperture. Potentials such as 200, 250 and 300 volts may be applied to the electrodes 11, 23 and 24 respectively, in which case $V_o=250$ and $V_o'=300$. For rejecting electrons having $V_r>0.2$ volt, Equation 14 becomes

$$\frac{r}{L_r} = \sqrt{\frac{0.2}{250}} \cdot \frac{2}{1 + \sqrt{\frac{300}{200}}}$$

$$\frac{r}{L_r} = \frac{1}{12.4}$$

Therefore for limiting and selecting apertures of 0.002" and 0.006" diameter respectively, the separation between the apertured electrodes 24-25 should be equivalent to L_r or 0.050 inch.

In the above description and calculations it is evident that the apertures in the limiting and selecting electrodes were chosen of unequal diameter with the limiting apertured electrode closer to the cathode, and that the limiting aperture was located at one of the points of focus of the beam. The tube will operate equally as well if the selecting apertured electrode is closer to the cathode than the limiting aperture. In addition, the diameters of these apertures may be equal or unequal, but for equal diameters the desired spacing between the electrodes is small and consequently such a structure is more difficult to construct.

I have constructed tubes in accordance with my invention designed to select and utilize only the electrons of the beam having radial velocities less than 0.6 volt and also less than 0.2 volt and have found that considerable improvement in resolution compared with tubes not utilizing my invention is obtained. I have also found that the resolution of which the tubes are capable is, in the latter case, substantially independent of the electron beam current for beam intensities usually used in such tubes.

While I have indicated the preferred embodiments of my invention of which I am now aware and have indicated the specific application as directed to cathode ray transmitting tubes having target electrodes of the photosensitive mosaic type, it will be apparent that my invention is by no means limited to the purpose of television transmission, to the exact forms illustrated, or to its use in cathode ray tubes incorporating target electrodes of the mosaic type, but that many variations may be made in the particular structure used, such as by replacing the mosaic electrode with target electrodes of the fluorescent, photoconductive, or photovoltaic type, without departing from the scope of the invention as set forth in the appended claims.

I claim:

1. A cathode ray tube system comprising a tube having an electron emitting source, a target to receive electrons from said source, a pair of separated apertured electrodes with their apertures lying along an axis between said source and said target to limit the flow of electrons therebetween, means to generate a longitudinal magnetic field extending between said source and said target, and means to maintain said two apertured elec-

trodes at the same positive potential with respect to said source, the sum of the radii of the two apertures of said apertured electrodes being represented by the expression

$$5 \quad L_r \sqrt{\frac{V_r}{V_o}}$$

where L_r is the separation no greater than one-half inch between adjacent surfaces of said electrodes in inches, V_o is the potential difference in volts between said electrodes and said cathode, and V_r is the maximum radial volt velocity of electrons in said beam and less than 0.6.

10 2. A cathode ray tube system as claimed in claim 1 wherein the radii of the apertures in said electrodes are unequal.

15 3. A cathode ray tube apparatus comprising a tube having an electron emitting cathode, an oppositely disposed target to receive electrons from said cathode, two apertured electrodes having their apertures aligned with an axis extending from said cathode to said target, means to generate a magnetic field extending along lines substantially parallel with said axis and between said cathode and said target, and potential means to maintain each of said apertured electrodes at positive potentials with respect to said cathode, the sum of the radii in inches of the two apertures in said electrodes being represented by

$$20 \quad L_r \sqrt{\frac{V_r}{V_o}} \cdot \frac{2}{1 + \sqrt{\frac{V_o'}{V_o}}}$$

25 35 where L_r is the separation no greater than one-half inch along said axis between said electrodes measured in inches, V_o' and V_o are the potentials in volts at which the said electrodes in their order of distance from the cathode are maintained by said potential means, and V_r is the maximum 40 radial volt velocity, less than 0.6, of electrons passing through the apertured electrode nearer said target.

4. Television transmitting apparatus comprising a cathode ray tube having an evacuated envelope, a magnetic coil surrounding said envelope, a cathode within said field to emit electrons of which a portion have radial volt velocities greater than 0.6, causing said portion of electrons to follow helical paths in said field and to 50 describe loops of focus between said cathode and target, two apertured electrodes having selected aperture diameters between said cathode and target and means to maintain said two electrodes at a single positive potential with respect to said 55 cathode, the sum of the radii of said apertures in inches being substantially equal to

$$55 \quad \frac{L}{n\pi} \sqrt{\frac{V_r}{V_o}} \sin \frac{n\pi L_r}{L}$$

60 60 where L is the distance in inches and n the number of loops of focus between said electrode nearer said cathode and said target, L_r is the separation in inches between said apertured electrodes measured in the direction of said field, V_o is the single 65 potential in volts at which said two electrodes are maintained, and V_r is the maximum radial volt velocity, less than 0.6, of electrons passing through the apertured electrode nearer said target.

5. Television transmitting apparatus comprising 70 a tube including an evacuated envelope, a magnetic coil surrounding said envelope to generate a substantially uniform magnetic field, a target in said envelope positioned in a plane substantially normal to said field, a cathode opposite said target and within said field to emit electrons 75

in the direction of said target, a portion of said emitted electrons having a radial volt velocity in excess of 0.6 causing said portion of electrons to describe helical paths in said field and to follow loops of focus between said cathode and target, a pair of apertured electrodes having selected aperture diameters between said cathode and target, and means to maintain said apertured electrodes at positive potentials with respect to said cathode, the sum of the radii of the apertures of said electrodes in inches being represented by the expression

$$\frac{L}{n\pi} \sqrt{\frac{V_r}{V_o}} \sin \frac{n\pi}{L} L_r \frac{2\sqrt{V_o}}{\sqrt{V_o} + \sqrt{V_o'}}$$

field between said apertured electrodes, V_o' is the potential in volts with respect to said cathode applied to the said electrode nearer the cathode, V_o the potential applied to the electrode nearer the target, L is the distance in inches, and n the number of loops of focus between the said electrode nearer said cathode and said target, and V_r is the maximum radial volt velocity, less than 0.6, of electrons passing through the apertured electrode nearer said target.

6. Apparatus as claimed in claim 5 wherein the apertures in said pair of electrodes are of unequal diameter, the electrode having the aperture of smaller diameter being nearer said cathode.

where L_r is the separation in inches along said

HENRY B. DE VORE.
